UNITED STATES PATENT OFFICE.

GEORGE P. FINDLAY AND WILLIAM W. JOHNSTON, OF WORCESTER, MASSACHUSETTS,
ASSIGNORS TO CROMPTON & KNOWLES LOOM WORKS, OF WORCESTER, MASSACHUSETTS, A CORPORATION OF MASSACHUSETTS.

KNIFE GRINDER FOR LOOMS.

Application filed November 19, 1923. Serial No. 675,467.

This invention relates to carpet looms of the Axminster type and particularly to improved mechanism for grinding the pile cutting knives in such looms. These looms are 5 now built of greater width than has been heretofore customary and accurate grinding of the longer knives has become correspondingly more difficult.

It is the object of our invention to provide 10 a grinding mechanism or attachment for such looms, by means of which the knives may be ground accurately and their outline preserved, without depending upon the skill of the operator to produce this result.

15 An important feature of our invention relates to the provision of an improved portable grinder having guiding and supporting elements by which it is well adapted to the purpose described.

20 Another feature relates to the provision of means for supporting and guiding the grinder on the knives while in the loom, to the end that an accurate edge of desired outline may be produced.

25 Our invention further relates to arrangements and combinations of parts which will be hereinafter described and more particularly pointed out in the appended claims.

A preferred form of the invention is 30 shown in the drawings in which—

Fig. 1 is a plan view of portions of the front and back knives of an Axminster carpet loom, with our improved grinder mechanism mounted thereon in position to grind 35 the front knife;

Fig. 2 is an enlarged sectional elevation, taken along the line 2—2 in Fig. 1;

Fig. 3 is a plan view of the grinder;

Fig. 4 is a side elevation thereof;

40 Fig. 5 is a sectional elevation, taken along the line 5—5 in Fig. 4;

Fig. 6 is a diagrammatic view similar to Fig. 2 but showing the grinder in position for grinding the back knife;

45 Fig. 7 is an edge view of one of the guiding or supporting bars;

Fig. 8 is a view showing the means for clamping one end of the grooved guide bar to the knife on which it is mounted;

50 Fig. 9 is a sectional elevation, taken along the line 9—9 in Fig. 8;

Fig. 10 is a front elevation showing the means for securing the opposite end of the

grooved guide bar to its supporting knife; and

55 Fig. 11 is a perspective view showing one of the gauge blocks by which the grooved guide bar is accurately located on the knives.

Referring to the drawings, we have shown a portion of a front knife 20 and a back knife 60 21 of the common form used in Axminster carpet looms. Our improved grinding mechanism comprises a grinding wheel W mounted on an arbor which is removably secured to the end of a grinding shaft 22 supported 65 and driven by a small high speed electric motor 23 suitably connected in any usual manner to a convenient source of power.

The casing of the motor 23 is provided with an offset projection 24 having a stud 25 70 projecting therefrom and rotatably mounted in a bearing 26 in a carriage or support 26. An arm 27 is fixed to the stud 25 and an adjusting screw 28 (Fig. 5) extends through a slot 29 in the arm 27 and is threaded in the carriage or support 26. A shoulder 30 on the screw 28 engages the outer surface of the arm 27 and a spring 31 yieldingly moves the arm 27 outward against the shoulder 30. By adjustment of the screw 28, the 75 grinding wheel W may be moved toward or from the knife edge during the grinding operation.

The carriage or frame 26 is provided with a pair of supporting lugs 32 (Fig. 4) and 80 also with a projecting arm 33 having an additional supporting lug 34. The lugs 32 and 34 are preferably of hardened steel and are adapted to slide upon guide bars 35 and 36. The guide bar 35 has a semi-circular groove 85 or recess in its upper face adapted to receive the supporting lugs 32, while the guide bar 36 has a flat upper face to support the lug 34. The two spaced lugs 32 and the single lug 34 provide a three-point support for the 90 grinder.

It is essential that the guide bars shall be accurately positioned on the front and back knives prior to the grinding operation and we have indicated in the drawings certain 100 special devices for locating and securing the guide bars.

The grooved guide bar 35 not only supports the grinder, but also guides the grinder relative to the edge of the knife to be ground. 105 Consequently it is essential that the bar 35

shall be secured at a uniform distance from the edge of the knife, and for this purpose we provide spacing or gauge blocks 37 as shown in Fig. 11. Each block has a spring plate 38 by which it may be temporarily held squarely against the bar 35 and has a shoulder or projection 39 adapted to engage the edge of the knife.

The bar 35 is provided with an inverted wedge 40 at one end thereof and with a screw 41 adapted to engage a fixed portion 42 of the loom and move the bar 35 longitudinally until the wedge 40 engages the under side of the knife and firmly seats the bar on the knife. When the bar 35 is thus positioned longitudinally by the screw 41 and has been adjusted transversely by the gauge blocks 37, a clamp 43 may be used to secure the opposite end of the bar in position and additional clamps may be used at intermediate points if found necessary, these clamps being singly removed to permit passage of the grinder along the knife. A spacing screw 44 (Fig. 9) may be threaded 25 in the bar 35 and may be used to prevent accidental transverse displacement of the bar 35.

The flat guide bar 36 need not be as accurately positioned on its knife and is provided with simple spring clips 45 (Figs. 2 and 6) by which it may be secured to the upper face of the knives 20 or 21. The bar 36 is shown as varying in thickness, (see Fig. 7) a construction required when the knives are not strictly parallel when in spaced relation.

In the use of our improved grinder mechanism, the guide bars 35 and 36 are first accurately located and secured to the knives 40 as above described and the wheel W is then adjusted by the screw 28 to engage the edge of the knife at the desired angle. The grinder is then moved back and forth along the knife and the grinder wheel is further advanced if necessary until the desired edge is secured on the knife.

The guide bars 35 and 36 are then interchanged and again adjusted and the second knife edge is then similarly ground. We have thus provided convenient and simple grinding mechanism by which the edges of long pile cutting knives may be conveniently and accurately ground without removing the knives from the loom.

Having thus described our invention and the advantages thereof, we do not wish to be limited to the details herein disclosed otherwise than as set forth in the claims, but what we claim is:—

1. A mechanism for grinding the knives of a carpet loom comprising a pair of guide bars, means to secure said bars in position on said knives when said knives are in spaced relation, and a sliding frame supporting a grinding wheel and driving mecha-

nism therefor, said frame being movable on and guided by said bars to present said wheel in predetermined relation to a knife edge.

2. A mechanism for grinding the knives of a carpet loom comprising a pair of guide bars, means to secure said bars in position on said knives when said knives are in spaced relation, and a sliding frame supporting a grinding wheel and driving mechanism therefor, said frame being movable on and guided by said bars to present said wheel in predetermined relation to a knife edge, and said frame having means to adjust the grinding wheel toward and from the knife edge.

3. A mechanism for grinding the knives of a carpet loom comprising a pair of guide bars, means to secure said bars in position on said knives when said knives are in spaced relation, and a sliding frame supporting a grinding wheel and driving mechanism therefor, said frame being movable on and guided by said bars to present said wheel in predetermined relation to a knife edge, and said frame having a three-point support on said bars.

4. A mechanism for grinding the knives of a carpet loom as set forth in claim 1, in which one of said guide bars is grooved to receive a pair of supporting lugs on said sliding frame and the other bar supports a third lug mounted on an offset projection of said frame.

5. A mechanism for grinding the knives of a carpet loom as set forth in claim 1, in which the securing means includes devices to clamp a guide bar to a knife, and means to adjust said part transversely on said knife.

6. A mechanism for grinding the knives of a carpet loom as set forth in claim 1, in which one of said guide bars has a plurality of gauge blocks detachably secured thereto for locating said bar on its knife.

7. A mechanism for grinding the knives of a carpet loom as set forth in claim 1, in which one of said guide bars has a plurality of gauge blocks detachably secured thereto for locating said bar on its knife, and in which said gauge blocks are each provided with a shoulder to engage the edge of said knife and position the bar relatively thereto.

8. A mechanism for grinding the knives of a carpet loom as set forth in claim 1, in which one of said guide bars has an inverted wedge to engage the lower face of its knife, and in which means is provided to move said guide bar longitudinally to firmly engage said wedge with said knife.

In testimony whereof we have hereunto affixed our signatures.

GEORGE P. FINDLAY.
WILLIAM W. JOHNSTON.
